UNITED STATES PATENT OFFICE.

MICHAEL H. BERNHARD, OF BUFFALO, NEW YORK, ASSIGNOR TO M. J. BERNHARD COMPANY, INC.

BALL-RETURN FOR POOL-TABLES.

1,137,736.

Specification of Letters Patent.

Patented May 4, 1915.

Application filed December 17, 1914. Serial No. 877,674.

To all whom it may concern:

Be it known that I, MICHAEL H. BERNHARD, a citizen of the United States, residing at Buffalo, in the county of Erie and 5 State of New York, have invented a new and useful Improvement in Ball-Returns for Pool-Tables, of which the following is a specification.

This invention relates to pool tables and 10 especially to ball holders or receptacles used in connection with ball return attachments therefor.

The invention is particularly adapted for use with tables located in public pool 15 rooms, where it is customary to charge a fixed amount for each game played and where at the end of each game an attendant replaces the balls on the table, taking them from the holder into which they gravitate 20 from the ball pockets. In this way the proprietor can check up the number of games played and charge accordingly. While various forms of ball holding receptacles have been used for this purpose heretofore, 25 none of them has been found entirely satisfactory, as in all of them it has been found awkward and difficult to take the balls out of the holder in order to replace them on the tables, or the construction of the holder 30 has been such that it has been easy for the players themselves to return the balls to the tables, thus avoiding payment for extra games played.

One object of the invention is to provide 35 a ball holder of simple, inexpensive and desirable construction from which the balls can be readily and easily removed when desired, and in which the balls are exposed to view and accessible so as to enable the cue 40 ball or other particular ball to be taken from the receptacle when this is necessary.

Another object is to construct the device in such manner as to prevent to a great extent the surreptitious return of the balls to 45 the table by the players.

In the accompanying drawings: Figure 1 is a plan view of a pool table with the top removed, showing a ball return device embodying the invention. Fig. 2 is a perspective view of the ball receptacle in position

at the end of the table. Fig. 3 is a similar view, showing the hinged member of the receptacle swung back so as to discharge the balls from the receptacle. Fig. 4 is a side sectional elevation, on an enlarged scale of 55 the ball receptacle, showing the discharge opening closed. Fig. 5 is a similar view with the bottom opening uncovered.

Referring to the drawings by numerals, 1 represents a pool table of ordinary construction having the usual pockets, indicated by dotted lines at 2. A series of inclined return channels or runways 3 of any suitable material and construction lead from the various pockets to the ball holder 4 and 65 serve as guides for directing the balls which are pocketed into the receptacle.

The ball holder, which may be constructed of wood or other suitable material, is preferably located under the "starting" end of the 70 table. It comprises an upper compartment or receiving tray 5 which is of sufficient size to accommodate all of the balls used in playing pool, and a lower compartment, shelf or support 6 adapted to support a 75 basket or other portable receptacle beneath the receiving tray 5. The receiving compartment or tray has side and end walls to confine the balls therein, and an open top which enables the balls to be seen and to be 80 picked out of the tray, if desired. In the preferred construction illustrated, the front portions 7 of the side walls 8 extend obliquely toward each other, and as the bottom 9 of the receiving tray is included 85 downwardly slightly toward the front thereof, these oblique portions 7 serve as guides to the balls which after entering the tray at the rear thereof gravitate toward the front wall 10 of the tray.

The bottom 9 has a cut away portion or opening 11, preferably of semi-circular shape, formed in the front edge thereof adjacent to the front wall 10 of sufficient size to allow passage for several pool balls simultaneously. This opening is normally closed by a flat cover or trap door 12 which corresponds in size and shape to the opening and fits therein, and this door is connected to and supported in any suitable manner by 100

the front wall 10 of the device from which it extends at substantially right angles.

13 represents arms or extensions extending obliquely from the upper edges of the front wall 10. These arms are adapted to rest in cut away portions 14 formed at the upper edges of the oblique walls 7 and are hinged at 15 to the upper front ends of the side walls 8 of the holder. In this way the door 12, wall 10 and arms 13 form together a movable or hinged member adapted to be swung upwardly and backwardly on its hinges 15 in order to open or uncover the opening 11 and allow the balls held in the upper receptacle or tray to pass through the opening into a portable basket or receptacle 16 of any suitable sort which is placed on the shelf or lower portion 6 of the device. This shelf 6 in the construction shown consists of a horizontal flat bottom portion connected by side walls 17 to the bottom of the upper tray or compartment and is adapted to support a basket or receptacle of sufficient size to hold all the balls used in a game of pool. As shown, the oblique walls 7 of the receiving tray extend beyond the side walls 17 of the shelf 6 so that when the movable door 12 is lifted, as described, there will be no possibility of the balls falling beyond the basket supported in the bottom of the holder.

In operation, the balls after being pocketed gravitate by means of the return channels 3 to the tray or upper compartment of the ball holder. When a game is finished and it is desired to replace the balls on the table, it is only necessary to grasp the front wall 10 of the receiving tray and swing the movable section upwardly, thereby uncovering the opening in the bottom of the tray and allowing the balls to pass through said opening into the basket supported below the tray. The balls will in this way be readily assembled in the basket and can be returned to the table without trouble. By having the receiving tray in which the balls collect and from which they are discharged into the portable basket or receptacle, instead of returning the balls directly from the return channels into a basket or portable receptacle in the first instance, the players themselves are not likely to attempt to return the balls surreptitiously to the table, as it is more troublesome and requires more time to pick them out singly from the receiving compartment. Furthermore, the attendant retains the basket in his possession and does not place it in position to receive the balls from the receiving tray until a game is finished. In order, therefore, for the players to replace the balls from the holder on the table, it would be necessary for them to pick the balls singly or a few at a time from the receiving tray.

35 The balls are nevertheless exposed to view

in the receiving tray so that the cue ball or any other particular ball can be readily picked out and placed on the table.

The movable section can be easily operated even when the top receiving tray has 70 all the balls assembled therein, and there is no danger of any of the balls "jumping" and falling upon the floor. When the hinged section is released after lifting it to discharge the balls, it will drop back into 75 place and there is therefore no danger of the discharge opening being accidentally left open and permitting the balls to fall to the floor, as is liable to happen in devices in which the closure for the discharge opening 80 must be replaced by hand in order to close the discharge opening.

I claim as my invention:

1. The combination with a pool table provided with ball return guides, of a ball 85 holder comprising a receiving compartment arranged to receive the balls from said guides and having a discharge opening in the bottom portion thereof, and a part adapted to support a portable receptacle in 90 position to catch the balls passing through said opening, and a self-closing member which closes said discharge opening and is adapted to be moved to permit the discharge 95 of the balls through said opening. 95

2. The combination with a pool table, of a ball holder having a ball receiving compartment comprising side walls provided with converging front portions having portions cut away at their tops, a bottom having an opening near the front thereof, a front wall supporting a door adapted to normally close said opening, arms connected with said front wall and hinged to said side walls so as to lie in the cut away portions 100 thereof, and a support for a portable receptacle. 105

3. The combination with a pool table provided with ball return guides, of a two-section ball holder arranged to receive the 110 balls from said guides, the upper section thereof having an opening in the bottom, side walls, and a front portion hinged to the side walls which normally serves to close 115 said opening but which can be swung upwardly so as to establish communication between the two sections of the holder.

4. The combination with a pool table provided with ball return guides, of a ball receptacle arranged to receive the balls from 120 said guides and having an upper and a lower compartment, the said upper compartment comprising a bottom having an opening at the forward part thereof, side walls, and a movable front wall pivotally connected with the side walls and having a door portion extending therefrom which is adapted 125 to fit into and normally close said opening in the bottom of the section. 125

5. The combination with a pool table, of 130

a ball holder mounted thereon comprising an upper portion having side walls with converging front portions, a slightly inclined bottom having an opening near the front thereof, a front wall connecting said side walls and having a door portion extending therefrom adapted to fit into and normally close the said opening, and arms

extending from said front wall and pivotally connecting the same with the side walls. 10

Witness my hand in the presence of two subscribing witnesses.

MICHAEL H. BERNHARD.
